(57) **CLAIM**

The ornamental design for a gun cleaning case, as shown and described.

DESCRIPTION

FIG. 1 is a front, left, top perspective view of a gun cleaning case, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof; and,

FIG. 9 is a front, left, top perspective view of the gun cleaning case in a detached state.

The short-short-long dashed broken lines immediately adjacent to the claimed areas in the views represent the boundaries of the design and form no part of the claimed design.

1 Claim, 9 Drawing Sheets
